SHOE SOLE

Henry Ghez and Oscar Ghez, New York, N. Y.

Application December 11, 1942, Serial No. 468,666

14 Claims. (Cl. 36—33)

The present invention relates to a built up or combined sole with or without a heel, or a heel, for shoes and footgear generally, to shoes, sandals and the like provided with such sole or heels, and also the process of making the same, and is an improvement related to those disclosed in our copending application Serial No. 443,648 filed May 19, 1942.

The main object of our invention is to utilize in the structure of a shoe sole a more or less massive flat member of stiff or at least somewhat stiff material, which is rendered resilient by the presence of a series of slots cut through the same alternately from one of the two side edges a distance toward the other.

Another object of the invention is to combine such a resilient member with a continuous sole member of flexible material and to assemble the same with an upper by sewing, nailing or cementing the latter thereto without weakening the combined sole or losing any of the resiliency thereof in or from the process.

A further object is to produce such a combined sole which will avoid the necessity of using any large amounts of leather, metal, plastics or rubber or other materials which may at times be expensive and even difficult to obtain.

It is likewise an object to have a combined sole of the indicated character for shoes, sandals, etc., which is substantially waterproof, has better wearing qualities than a leather sole, is light, hygienic, flexible, quiet in use and also anti-skid in nature, and which may also be used to establish new styles or vogues in footwear.

Other objects and the numerous advantages of our invention and accruing from its use in the art will appear more fully as this specification proceeds.

In order to bring out the construction and nature of the invention in more comprehensible manner, the same is illustrated in the accompanying drawings forming part hereof, and in which,

Fig. 1 is a transverse section of a shoe provided with a sole made according to our invention and embodying the salient features thereof in practical form, the section being taken on line 1—1 in Fig. 6.

Fig. 2 is also a transverse section of the same as taken on line 2—2 in said Fig. 6.

Fig. 3 is a section showing a modification of the shoe sole of Fig. 2.

Fig. 4 diagrammatically illustrates one way of forming and assembling the sole of the shoes shown in Figs. 1 and 2.

Fig. 5 is a fragmentary perspective of the sole with a portion raised to reveal more clearly certain details of its construction.

Fig. 6 is a bottom plan view of the shoe and 5 particularly the sole of Figs. 1 and 2.

Fig. 7 is a similar view of a heel made along the same lines of construction.

Fig. 8 is a longitudinal section of said heel, taken on line 8—8 in Fig. 7.

10 Fig. 9 is a fragmentary transverse section of a sole which is a modification of that of Figs. 1 and 2.

Fig. 10 is also a fragmentary section showing another modification.

15 Fig. 11 shows a different modification.

Fig. 12 is a plan view of a sole having a resilient member embedded therein to form a more or less resilient filler of firm material, the main portion of the sole being of resilient material.

19 Fig. 13 is a longitudinal section of the same taken on line 13—13 of Figure 12.

Fig. 14 is a transverse view of a further modification of the sole of Figures 1 and 2.

Fig. 15 is yet another modification in section.

25 Fig. 16 is a somewhat different modification of the same sole as shown in Fig. 15.

Fig. 17 is likewise an additional modification.

Fig. 18 is a modification having not only a lower rand but also an upper rand.

30 Fig. 19 is a modification of the sole shown in Fig. 18.

Throughout the views, the same references indicate the same or like parts.

At certain times when leather, rubber and 35 even some plastics are in such heavy demand that their cost rises considerably and they may even become difficult to obtain in any satisfactory quantities, it is desirable in the manufacture of footgear to make at least the sole of the same

40 of a minimum of these materials while using certain other more common materials in novel forms of construction to constitute excellent contributions to the art.

It is therefore proposed to use other materials 45 to form the bulk of a sole or the like and only a small fraction of the usual proportion of rubber or plastics, etc., while certain novel features of construction are combined in such manner as to introduce a group of decided advantages into the field of shoe soles.

Hence, in the practice of our invention, a shoe 50 generally indicated at 12 has an upper 13 attached to a sole generally indicated at 14. This sole consists mainly of a body member 15 of plywood, plain wood, plastic wood, molded plastics,

hard rubber, molded fibrous material, cork board, cork agglomerate, cork vulcanized fiber, paste-board and the like, or any other normally stiff material which would be too rigid for use if not modified as will be immediately explained. This body member is preferably substantially flat and is alternately slotted from the two side edges thereof to form a series of alternating open slots 16, 17, etc., each open slot extending a limited distance inward upon the sole from its respective edge. These slots may be convergent or divergent, parallel, non-parallel, straight, curved or zig-zag shaped, and their side walls may be convex, concave, and parallel, convergent or divergent from the upper surface to the lower or from one end of the slot to the other.

Due to the presence of the open slots, or the like, the body member 15 is rendered flexible and in fact resilient so that, while it may be very light when it consists of wood or wood veneers, yet the resiliency is superior to that of a solid rubber sole of equal size when made of that type of rubber used for soles and heels, this rubber being of course very much heavier than said wooden member. In order to present a finished and continuous peripheral edge to the floor or ground upon the sole, and also in order to connect the outer ends of the slots and prevent undue spreading or expansion of each individual slot, a continuous rand or rim 18 of vulcanized rubber, leather, or flexible plastic of the vinyl series or any other is fixed in a marginal recess or shoulder 19, about the entire perimeter of the body member 15. The rubber, leather or plastic rand 18 may be flush with the bottom surface 20 of the body member 15, when the slotted condition of said body member will serve as an anti-skid surface for the sole.

On the other hand, it is desirable to render the sole waterproof and also present a continuous and unbroken upper surface upon the same to the foot of the wearer and hence a sheet of rubberized or waterproofed fabric or any other more or less flexible material 21 is cemented or otherwise secured to the upper surface of the wooden body member 15.

With the sole assembled as just described, the upper 13 is secured to said sole by stitching 22, 22, by nailing, or cementing to the waterproofed sheet 21, when the shoe will be found to be light, flexible and quite elastic due to the presence of the resilient body member 15, while the appearance of the sole will be such as to mark a new vogue and form a nucleus for a group of new styles.

It is quite evident that the marginal portion about the body member 15 is thinner than the central portion due to the material removed in order to form the marginal recesses or shoulders, so that it is actually possible to stitch through the wood as well as through the rubber and the waterproofed material 21. However, if the slots 16 and 17 were left open the threads during sewing would become slack, while crossing said slots and the tension of the stitches would be spoiled so that it is very conceivable that loose loops would occur, uneven stitching, and even frequent breakage of the threads, all of which would be highly unsatisfactory. Thus, in order to make it possible to maintain a continuous proper tension of the threads and a tight resulting condition of the stitches, the material of the rand 18 during manufacture of the sole is forced into at least the outer ends of the slots to a width corresponding approximately to the width of the rubber rand as indicated in Figs. 2 and 5 at 23. Of course, if it should be desired to completely fill the slots with

the material forming the rand as shown at 24 in Figure 3, this can be done quite readily although the resiliency of the sole is in some cases somewhat damped and the weight is noticeably increased, not to mention that more rubber is used.

When assembling the sole a preformed blank 21 of rubberized fabric, or other material is first inserted into a die 25, and the body member 15 laid upon the same with its flat surface facing downwardly and then a rubber rand blank 18 is deposited in the marginal recess of the body member 15, the rand blank projecting more or less above the general surface of the body member and preferably consisting of a semi-hard form of rubber or plastic. At most the rubber rand should only be semi-cured so that when an upper die member 26 is pressed down upon the rand some of the material thereof will by extrusion enter the slots 16, 17 and extend down to the waterproofed material 21 and incorporate therewith. It may be mentioned that the rubberized material may well be covered with a coating of cement in order to encourage adhesion thereof to the wooden body member after pressure has been applied, while the contact of the rubber material from the rand through the marginal portions of the slots 16 and 17 will form a good cemented joint in each case so as to tend to retain the waterproofed sheet in assembled relation to the sole.

As shown in Figures 7 and 8, a heel generally indicated at 27 may alone be constructed along the same lines as just described with respect to a whole sole so that a rubber rand 28 is present to form a marginal portion upon a wooden or other main body 29, which is slotted at 30, 31, etc., alternately from the opposite edges as before, while the upper surface is protected by a coating or sheet 32 of waterproofed material.

Instead of depositing the rubber rand directly in the recess so as to come into direct contact with the wooden body member, it is desirable in some cases to interpose a strip 33 of waterproofed material, such as rubberized fabric or other sheet material prior to placing the rand in position and pressing the same into intimate contact with said strip and by means of the pressure applied, simultaneously causing adhesion of the strip itself to the surface of the recess, thus bonding the rubber rand 34 to the wooden body member 15. In corresponding manner a strip or sheet 35 of rubber having the same approximate width as that of recesses may be laid upon the upper surface of the wooden body member along the edge thereof, and the sheet of waterproofed material 21 applied on top of the same and the pressure applied to the whole to unite the various parts into a composite resilient unit.

It is sometimes also desirable to increase the contact surface and thereby the adhesion between the side and bottom of the recesses and the rubber rand and this may be accomplished by serrating the surface involved as indicated at 36, 37 which will cause the rand 38 to adhere very firmly to the wooden or plastic body member 39, which of course has an upper waterproofed sheet or coating 21.

Furthermore, the body member 40 having the usual upper waterproofed coating or sheet 21 with a marginal recess 41 may also have a high rand 42 of rubber, leather or plastic, etc., which projects a distance beyond the lower surface 43 of the body member 40 as particularly shown in Figure 11, while the edges of the rand may be made square as shown, or bevelled, or rounded according to desire.

In Figures 12 and 13 a form of the sole generally indicated at 44 is shown in which the resilient member 45 has the alternately cut slots 46, 47, etc., but is merely of sufficient length to occupy the heel and instep portions of the sole, whereas the forward portion 48 which takes the greater wear and also requires to be very resilient is preferably of solid rubber or resilient plastic. In this case the bottom of the sole at 49 may be rather thin so as merely to cover the resilient member 45, while the marginal edge portion 50 will serve well for receiving stitches, nails, or the like when securing the sole to an upper.

In Figure 14 a similar structure is shown as in the case of the sole shown in Figures 1 and 2, except that the top layer of fabric or rubberized material is omitted. The body member 51 is similar to that of Figures 1 and 2, while the slot 52 represents the alternate slots and the rand or rim 53 occupy the recess 54 so as to bridge the outer ends of the slots and between the slots extends up to the top of the body member as shown at 23. The form of sole shown in section in Figure 15 has a body member 55 wherein a bottom rand 56 of rubber, leather or flexible plastic occupies a recess as before, while in a marginal position to match the position occupied by the rand is a strip of leather, rubber, fabric, resilient plastic, or rubberized fabric, or other material 57 secured to the upper surface 58 of the body member. In order to secure this upper strip more perfectly the material of the lower rand 56 when of rubber or resilient plastic may be forced up into the slot 55 as shown at 59, and thereafter vulcanized or set as particularly shown in Figure 16. In all other particulars the structure as in Figure 16 are the same as corresponding portions or members in Figure 15. The body member 60 of the sole shown in Figure 17 has a lower rand 61 and is of course slotted as indicated at 62, but instead of having a completely covering upper sheet similar to 21 in Figures 1, 2 and 3, a smaller and more limited piece of material 63 is attached to the upper surface 64 of said body member, which may either be recessed into this member so that the upper surface is flush with surface 64, or it may overlie the top as illustrated in said Figure 17.

In most of the figures previously described a single rand has been shown as occupying a recess in the lower edges of the sole, but it is quite evident that as shown in Figure 18 a body member 65 slotted as before at 66 may have an upper rand 67 occupying an upper marginal recess 68 in addition to the lower recess 69 which occupies the lower marginal recess 67. The two rands may be of the same material or of entirely different materials if so desired, and in either or both cases the rands may be of leather, rubber or resilient plastic. It is quite desirable to have the upper and lower rands connected intimately so that they not only will be retained in position but will cooperate to retain the slotted body member 65 within bounds and prevent undue flexure which might cause fracture. In Figure 19 the upper rand 67 is connected with the lower rand 69 by 65 means of the intermediate portion 70 of the material of either or both of said rands which extend between the two in the outer end of slot 66. While it has been stated that the resilient member in the sole is preferably of wood or plywood, etc., it is obvious that the same can be wholly or only partly of firm or rigid plastic material which may include any one or more of the known plastics, while the remainder of the resilient member may be of wood or plywood if the same consists

only partly of such plastics. It is also quite evident that the slots may be greater or fewer in number than actually shown in the drawings for a given shoe sole, while in every case said member 55 serves either as the main bulk of the sole, or at least as considerable filler in the structure thereof.

The invention may be used as an insole, half sole, outer main sole with heel or any part of a sole or a heel for footwear. Manifestly, variations in the materials used and the forms of the parts involved may be resorted to within the scope of the appended claims.

Having now fully described our invention, we claim:

15. An outer sole or the like for footwear comprising the combination of a main body member of normally stiff material having the outline of at least a half sole and a series of transverse slot portions cut entirely through the thickness of said body member alternately from each side edge a limited distance toward the opposite side edge, a continuous layer or coating of flexible material secured upon the upper surface of said body member so as to bridge all the slot portions therein, and a rand or marginal strip of flexible material occupying a perimetral recess in the edge of the opposite or lower surface of the body member so as to bridge the outer ends of said slot portions.
20. An outer sole or the like for footwear comprising the combination of a main body member of normally stiff material having the outline of at least a half sole and a series of transverse slot portions cut entirely through the thickness of said body member alternately from each side edge a limited distance toward the opposite side edge, and a continuous layer or coating of waterproofed flexible material secured upon the upper surface of said body member so as to bridge all the slot portions therein, and a rand or marginal
25. strip of elastic material of the class consisting of rubber, vinyl plastics and other resilient plastics occupying a perimetral recess in the edge of the opposite or lower surface of the body member so as to bridge the outer ends of said slot portions.
30. An outer sole or the like according to claim 1, the layer of flexible material being selected from a class consisting of rubberized fabric, waterproofed paper, waterproofed fabric, waterproofed leather, and having the rand in the recess upon the lower surface made of elastic material.
35. A sole or the like according to claim 1, having the rand projecting beyond the lower surface of the body member.
40. A sole or the like according to claim 2, having the elastic material of the rand projecting up through the outer ends of the slot portions into intimate contact with the under side of the continuous layer of material on the upper surface of the body member, the intermediate parts of the slot portions being free from said elastic material.
45. A sole or the like according to claim 2, having the elastic material of the rand projecting up through the slot portions into intimate contact with the under side of the continuous layer of material on the upper surface of the body member.
50. A sole or the like according to claim 2, having the rand projecting beyond the lower surface of the body member.
55. A heel for a shoe or other footwear having a sole, comprising the combination of a main body member of normally stiff material having the outline of a heel and a series of transverse slot portions cut entirely through the thickness of said body member alternately from each side

edge a limited distance toward the opposite side edge, a continuous layer or coating of flexible material secured upon the upper surface of said body member so as to bridge all the slot portions therein, and a rand or marginal strip of flexible material occupying a perimetral recess in the edge of the opposite or lower surface of the body member so as to bridge the outer ends of said slot portions.

9. A sole and heel for footwear comprising the combination of a main body member of normally stiff material having the outline of both sole and heel in assembled condition, and a series of transverse slot portions cut entirely through the thickness of said body member alternately from each side edge a limited distance toward the opposite side edge, a continuous layer or coating of flexible material secured upon the upper surface of said body member so as to bridge all the slot portions therein, and a rand or marginal strip of flexible material occupying a perimetral recess in the edge of the opposite or lower surface of the body member so as to bridge the outer ends of said slot portions.

10. An outer sole or the like for footwear comprising the combination of a main body member of normally stiff material having the outline of at least a half sole and a series of transverse slot portions cut through the entire thickness of said body member alternately from each side edge a limited distance toward the opposite side edge, a continuous layer or coating of waterproofed flexible material secured upon the upper surface of said body member so as to bridge all the slot portions therein, and a rand or marginal strip of resilient material including leather occupying a perimetral recess in the edge of the opposite or lower surface of the body member so as to bridge the outer ends of said slot portions.

11. A sole or the like for footwear comprising the combination of a main body member of normally stiff material having the outline of at least a half sole and a series of transverse slot portions cut through said body member alternately from each side edge a limited distance toward the op-

posite side edge, and a rand or marginal strip of flexible material occupying a perimetral recess in each of the upper and lower surfaces of said body member so as to bridge the outer ends of said slot portions.

12. A sole or the like for footwear comprising the combination of a main body member of normally stiff material having the outline of at least a half sole and a series of transverse slot portions cut through said body member alternately from each side edge a limited distance toward the opposite side edge, and a rand or marginal strip of flexible material occupying a perimetral recess in each of the upper and lower surfaces of said body member so as to bridge the outer ends of said slot portions, at least one of the rands being made of elastic material of the class consisting of rubber, vinyl plastics and other resilient plastics, and some of the material of at least one of said rands extending into the ends of the slot portions into effective contact with the other rand.

13. A sole or the like for footwear comprising the combination of a main body member of normally stiff material having the outline of at least a half sole and a series of transverse slot portions cut through said body member alternately from each side edge a limited distance toward the opposite side edge, and a rand or marginal strip of elastic material of the class consisting of rubber, vinyl plastics and other plastics occupying a perimetral recess in the edge of the lower surface of said body member with some of the elastic material of said rand extending up through the outer ends of said slot portions to the upper surface of the body member so as to bridge and close said outer end of the slot portions.

14. A sole or the like according to claim 2, wherein the layer of flexible material applied to the upper surface of the body member is selected from the class consisting of rubberized fabric, water-proofed paper, water-proofed fabric and water-proofed leather.

HENRY GHEZ.
OSCAR GHEZ.
